UNITED STATES PATENT OFFICE.

ALLEN JOHNSTON, OF OTTUMWA, IOWA.

PULLEY.

No. 839,596.

Specification of Letters Patent.

Patented Dec. 25, 1906.

Application filed September 7, 1904. Serial No. 223,647.

To all whom it may concern:

Be it known that I, ALLEN JOHNSTON, of Ottumwa, Iowa, have invented a new and useful Improvement in Pulleys, which invention is fully set forth in the following specification.

This invention relates to improvements in ball-bearing wheels, pulleys, or rollers for sheaves, sash-pulleys, door-hangers, and analogous devices. Heretofore such wheels or rollers, when formed of sheet metal, have commonly been made of two disk-like parts or halves secured together by rivets or otherwise. When subjected to heavy pressure or strains, the parts frequently break apart.

My object is to overcome this difficulty and to provide ball-bearing wheels or rollers of minimum cost and maximum strength and durability; also, to provide for maximum ball-bearing surface relative to the diameter of the wheel or roller.

The invention may be readily understood by reference to the accompanying drawings, wherein—

Figures 1 and 5 illustrate blanks from which parts of the wheel may be formed. Figs. 2, 3, and 4 illustrate different steps in the formation of the rim of the wheel. Figs. 6, 7, and 8 illustrate steps in the formation of the inner ball-retaining ring of the wheel. Fig. 9 is a sectional view, and Fig. 10 a side elevation, showing the parts secured together to form a completed wheel. Fig. 11 is an elevation, and Fig. 12 a sectional view, of a sheave or pulley in which the wheel shown in Fig. 9 is used. Fig. 15 shows the rim and ring in relative position before they are secured together.

In forming the outer grooved rim of the wheel I may start either with the flat sheet metal blank 15 or with the short tubular blank 16. When blank 15 is utilized, it is first drawn or shaped into the form of a cup, Fig. 2, having a bottom 17 and a flared open end forming a peripheral flange 18. By the next step of the process the bottom 17 is stamped out or otherwise removed, as shown in Fig. 3, leaving a slightly-inturned annular flange 19. The article of Fig. 3 is then further drawn, swaged, or shaped to turn the flange 19 outwardly, forming a second peripheral flange 20, similar to flange 18, said flanges being connected by a concave wall 21. The result of these operations is a continuous annular seamless rim formed of a single piece of metal and having side guide-flanges

18 and 20, separated by a peripheral groove 22, in which a sash-cord, track, or other coöperating part is adapted to engage. As shown, the rim is webless and spokeless—i. e., there is no portion or spokes extending inwardly from its inner convex surface. Fewer steps are required to form this rim from the tubular blank 16. One or two forming steps suffice to turn up the flanges 18 and 20 at opposite ends of the short length of tubing.

The inner trough-like ring for engaging the bearing-balls may be formed either from the circular sheet-metal blank 25 or the short tubular blank 26, Fig. 5. When the former is utilized, it is first drawn or shaped to form the cup of Fig. 6, having bottom 27. The edge of the cup is then turned inward to form a flange 28, Fig. 7. Bottom 27 is then removed and inturned flange 29 (similar to 28) formed. These operations result in the continuous seamless annulus or ring formed of a single piece of metal and having inturned ball retaining and engaging flanges 28 and 29.

The ring 30, (shown in Fig. 8,) is next inserted in the rim of Fig. 4, in which it closely fits, as shown in Fig. 15. The ring is now spread or expanded, particularly at its edges, until its wall assumes a shape corresponding to the inward convexity of the rim, as clearly shown in Fig. 9. Peripheral ribs 40 and 41 are thus formed. They are of greater diameter than the smallest diameter of the rim, and hence bind the rim and inner ring together. In this manner the two parts of the wheel are rigidly and securely fastened together without the use of rivets or solder. Solder, rivets, or other means of securing these parts together may, however, be employed.

The sheave or pulley shown in Figs. 11 and 12 comprises a wheel such as shown in Fig. 9, and two plates 32 and 33, rigidly connected by a bent-over flange 34 and so shaped as to provide a grooved annular ball-raceway 35. 36 represents bearing-balls operating in said raceway 35 and in the trough-like inner ring 30 of the wheel. The flanges 28 and 29 of said ring hold the wheel in proper operative position relative to the balls. It will be observed that the diameter of the wheel at the bottom of its peripheral groove exceeds the diameter of the bearing-surface for the balls (the inner peripheral wall of ring 30) by only four thicknesses of sheet metal. It follows that as compared to wheels which have their bearing-surface nearer the center there is less

- strain upon the wheel, many more balls can be employed, with corresponding increase in bearing-surface, the pulley is much stronger, more durable and lasting, there is greater smoothness of operation, and a smaller wheel can be employed for heavier work.
- Modifications may of course be made within wide limits without departing from the nature and principle of the invention.
10. What I claim is—
1. In a wheel or pulley, a continuous webless seamless rim having outwardly-projecting integral flanges at its opposite edges in combination with an inner ring fitting closely within said rim.
  2. In a wheel or pulley, a continuous webless seamless rim having outwardly-projecting integral flanges at its opposite edges, said rim and its flanges being formed of a single piece of sheet metal, in combination with an inner continuous seamless ring fitting closely within said rim.
  3. A wheel or pulley having a continuous seamless rim provided with outwardly-projecting integral flanges at its opposite edges, and an inner ring fitting closely within the rim and provided with inwardly-projecting integral flanges at its opposite edges.
  4. A wheel or pulley having a continuous seamless rim provided with outwardly-projecting integral flanges at its opposite edges, and an inner continuous seamless ring fitting closely within the rim and provided with inwardly-projecting integral flanges at its opposite edges.
  5. A wheel or pulley having a continuous seamless rim provided with outwardly-projecting integral flanges at its opposite edges, said rim and its flanges being formed of a single piece of sheet metal; and an inner continuous seamless ring fitting closely and secured within the rim and provided with inwardly-projecting integral flanges at its opposite edges, said ring and its flanges being formed of a single piece of sheet metal.
  6. A wheel or pulley having a rim, and a ring fitting within the rim and provided with peripheral ribs engaging on opposite sides of a portion of the rim of smaller diameter than the ribs, whereby the rim and ring are held together.

7. A wheel or pulley having a peripherally-grooved rim, a ring fitting closely within the rim and provided with inwardly-projecting flanges around opposite edges of the ring and peripheral ribs engaging on opposite sides of a portion of the rim of smaller diameter than the ribs, whereby the rim and ring are held together. 55

8. A wheel or pulley having a continuous seamless peripherally-grooved rim, a continuous seamless ring fitting within the rim and provided with inwardly-projecting flanges around opposite edges of the ring and peripheral ribs engaging on opposite sides of a portion of the rim of smaller diameter than the ribs, whereby the rim and ring are held together. 60

9. A wheel or pulley having a continuous seamless peripherally-grooved rim made of a single piece of metal, a continuous seamless ring made of a single piece of metal and fitting within the rim and having inwardly-projecting flanges around its opposite edges and peripheral ribs engaging on opposite sides of a portion of the rim of smaller diameter than the ribs, whereby the rim and ring are held together, said flanges and ribs being integral parts of the ring. 70 75

10. A wheel or pulley having a continuous seamless rim made of a single piece of metal, a continuous seamless ring comprising inwardly-projecting side flanges connected by a concave wall closely engaging an inwardly-convex wall of the rim, thereby securing the rim and ring together. 80 85

11. The combination with a wheel having a continuous seamless rim, and a concentric continuous seamless ring fitting closely and secured within the rim and formed with integral inwardly-bent ball retaining and guiding flanges at its opposite edges, of a gang of bearing-balls engaging the inner surface of the ring between said flanges, and a support for said balls. 90 95

In testimony whereof I have signed this specification in the presence of two subscribing witnesses.

ALLEN JOHNSTON.
